Primary Examiner — Cynthia Ramirez*Assistant Examiner* — Tamara L Hahn(74) *Attorney, Agent, or Firm* — Chrisman Gallo Tochtrip LLC(57) **CLAIM**

The ornamental design for a ladder for telescopic lifter, as shown and described.

DESCRIPTION

FIG. 1 is a front, right, top perspective view of a ladder for telescopic lifter, showing my new design;

FIG. 2 is a left side view thereof;

FIG. 3 is a right side view thereof;

FIG. 4 is a back view thereof;

FIG. 5 is a front view thereof;

FIG. 6 is a top view thereof; and,

FIG. 7 is a bottom view thereof.

The broken lines shown in the drawings depict portions of the ladder for telescopic lifter that form no part of the claimed design.

1 Claim, 3 Drawing Sheets(56)
